ATTORNEY.

UNITED STATES PATENT OFFICE.

LUEDER RASCHEN, OF SAN FRANCISCO, CALIFORNIA.

SNOW-REMOVING APPARATUS.

980,332.

Specification of Letters Patent. Patented Jan. 3, 1911.

Application filed September 3, 1910. Serial No. 580,346.

To all whom it may concern:

Be it known that I, LUEDER RASCHEN, a citizen of the United States, residing at San Francisco, in the county of San Francisco and State of California, have invented new and useful Improvements in Snow-Removing Apparatus, of which the following is a specification.

The present invention relates to an apparatus for removing snow from streets, roads, and railways, the object of the invention being to provide an apparatus of this character which will be of greater efficiency, power, and convenience than those heretofore used.

15 In the accompanying drawing, Figure 1 is a vertical longitudinal section of an apparatus constructed in accordance with my invention; Fig. 2 is a broken plan view thereof.

20 In the present instance, I have illustrated my invention as installed upon an automobile for the purpose of removing the snow from streets or roads, but it will be evident from the disclosure of its construction that 25 it can be equally well applied to locomotive engines or cars for the purpose of removing the snow from railways.

Referring to the drawing, 1 indicates an automobile, the detailed construction of 30 which is immaterial to the present invention, and its disclosure is therefore omitted. Upon the front portion of said automobile is mounted the casing of a combustion chamber 2, comprising a base plate 3, a back 4 sloping rearwardly upward, and a combined 35 top and sides 5 also sloping rearwardly upward. The said sides are spaced from said base plate a short distance to provide a narrow outlet 6 for the hot gases from the combustion chamber. Said plate is wedge-shaped or triangular in form, and the sides are also wedge-shaped. The outlet 6 is therefore also wedge-shaped, so that the hot gases issuing from said outlet are directed 40 laterally and forwardly.

7 indicates an oil burner connected with an oil tank 8, and directed forwardly into said combustion chamber. Also directed into said chamber are the front ends of air 45 conduits 9, which are connected with a common conduit 10 leading from a blower 11 driven from a gasoline engine 12 carried upon the automobile. The air thus directed into said combustion chamber not only insures perfect combustion of the oil but also

produces a great volume of heated air, which issuing from the outlet 6 with great pressure, is discharged to a considerable distance, and melts the snow within a considerable range on each side of the automobile. 60 A chimney 13 having a damper 14 is provided by which the products of combustion can be allowed to escape, when it is desired that they should not pass through the outlet 6. Lateral outlets 15 are supplied to said 65 chimney, either of which, if desired, can be connected with a hose for discharging the heated air at a considerable distance from the vehicle.

It is to be understood that I do not limit 70 my invention to the precise details of construction herein shown as they may be varied considerably without departing from the spirit of the invention.

I claim:—

1. In combination with a vehicle, and means carried by the vehicle for propelling the same, a combustion chamber arranged at the front end of the vehicle and having, close to the ground, an outlet arranged to direct 80 the products of combustion horizontally and in a partly forward and partly lateral direction, on each side of the vehicle, means carried by the vehicle for producing said products of combustion and means carried 85 thereby for forcing them through said outlet, substantially as described.

2. In combination with a vehicle, and means carried by the vehicle for propelling the same, a combustion chamber arranged at 90 the front end of the vehicle and having, close to the ground, an outlet arranged to direct the products of combustion horizontally and in a partly forward and partly lateral direction, on each side of the vehicle, a horizontal base plate extending outwardly beyond said outlet, means carried by the vehicle for producing said products of combustion and means carried thereby for forcing them through said outlet, substantially 95 100 as described.

3. In combination with a vehicle, and means carried by the vehicle for propelling the same, a combustion chamber arranged at the front end of the vehicle and formed in 105 close proximity to the ground with an outlet opening which is wedge-shaped in form and directed laterally and forwardly, means carried by the vehicle for producing said products of combustion and means carried 110

thereby for forcing them through said outlet, substantially as described.

4. In combination with a vehicle, a combustion chamber arranged at the front end of the vehicle, and having an outlet in proximity to the ground, vertical and lateral pipes for the escape of the hot gases from said combustion chamber, means for controlling the passage of the gases through 10 said pipes, and means for discharging hot

gases into said combustion chamber, substantially as described.

In testimony whereof I have hereunto set my hand in the presence of two subscribing witnesses.

LUEDER RASCHEN.
